E. T. BURLTON,
BOX COVERING MECHANISM.
APPLICATION FILED MAR. 25, 1916.

1,282,747.

Patented Oct. 29, 1918.

UNITED STATES PATENT OFFICE.

EDWARD THOMAS BURLTON, OF LONDON, ENGLAND, ASSIGNOR TO STOKES & SMITH COMPANY, OF SUMMERDALE, PHILADELPHIA, PENNSYLVANIA, A CORPORATION OF PENNSYLVANIA.

BOX-COVERING MECHANISM.

1,282,747.

Specification of Letters Patent. Patented Oct. 29, 1918.

Application filed March 25, 1916. Serial No. 86,566.

To all whom it may concern:

Be it known that I, EDWARD THOMAS BURLTON, a subject of the King of Great Britain and Ireland, residing in the city 5 and county of London, England, have invented new and useful Improvements in Box-Covering Mechanism, of which the following is a specification.

This invention relates to certain novel 10 and useful improvements in box covering mechanism and has particular application to means for covering cardboard and other boxes with adhesive wrappers or coverings which overlie not only the outside of the 15 box, but are turned over the edges of the latter and affixed to the inside thereof.

In the present instance my invention is particularly adapted for the covering of 20 box lids or similar structures having less than four sides, or boxes with falling fronts or high ends.

In covering boxes or lids of this class, it 25 is the practice to fold over and affix the marginal edge portions of the cover to the inside faces of the box or lid, and for this purpose machines have been employed embodying fingers for engaging the flaps of the cover to turn the latter inward of the 30 box or lid; these flaps or marginal portions of the cover being usually vertically disposed when being applied to the box or lid.

In carrying out the present invention, it 35 is my purpose to provide means by which the turned in flaps may be more efficiently affixed and caused to more closely adhere to the inner side of the box or lid. It is also my purpose to subject the flaps of the cover to a direct pressing action, after such flaps have been turned in, so as to insure the 40 complete adhesion between the flaps and the inner surface of the lid.

Furthermore, I propose to provide a covering mechanism which will embody the desired features of simplicity, reliability and 45 convenience.

With the above recited objects and others of a similar nature in view, my invention consists in the construction, combination and arrangement of parts set forth in and 50 falling within the scope of the appended claims.

In the accompanying drawings,

Figure 1 is a top plan view of the middle form block of a box covering machine

equipped with my invention, the pressure 55 blocks embraced in such invention being shown in their normal, non-expanded position.

Fig. 2 is a view in side elevation showing the three form blocks for operating 60 upon the box or box lid, the present blocks being shown in normal, non-expanded position.

Fig. 3 is a similar view illustrating the 65 pressing action in which the blocks are expanded against the flaps as in applying the cover to the box or lid.

Fig. 4 is a detail view showing a modified form of the device.

Fig. 5 is a perspective view of a three 70 sided box lid and showing the cover applied thereto with the marginal edges and flaps of the cover ready to be turned in against the inside of the box.

Before entering into a detailed description 75 of the invention, I will briefly state that in the preferred form shown herein the vertical cover flaps, after they have been turned in, are adapted to be subjected to a direct pressing action so as to insure the 80 complete adhesion between the flaps and the inner surface of the box or lid.

For this purpose, a convenient part of 85 the mechanism, preferably one of the form blocks on which the box or lid is placed, may be provided with a pair of sliding pressing blocks, which, after the vertical flaps have been turned in, are caused to move outwardly so that their faces press the flaps against the inner surface of the 90 sides of the box or lid, which are supported as usual in machines of this class, by external pressers or other suitable means. The sliding pressing blocks may be fitted to either the top or the middle form block, but 95 preferably the middle form block is employed, and these blocks are controlled and actuated by a wedge device mounted on the top form block, which, when the top form block descends upon the middle form block 100 at the final operation, forces apart the two sliding pressing blocks so that their outer faces press upon the flaps of the cover.

While the preferred form of pressing device, above mentioned, may be conveniently 105 fitted to a form block, as shown herein, it may in some cases be carried by other parts of the box covering machine, such as the

mechanism which operates the usual external pressers and the turning in fingers heretofore recited.

Referring now to the accompanying drawings in detail, and particularly to Figs. 1-3 inclusive, the letter A indicates the middle form block; B designates the top form block, while the bottom or under form block is shown at C. The box or box lid 5 to be covered is conveniently shown at D and is illustrated in detail in Fig. 5, the cover being indicated as an entirety at D', this cover having small vertical flaps d, which in Fig. 1 are shown in full lines as 10 turned in against the adjacent side walls of the box or box lid, this turning in having been accomplished by means of suitable fingers or other mechanism. In order to firmly and securely press these vertical turned in 15 flaps d against the inside of the box or box lid, I preferably mount upon the middle form block A, a pair of oppositely disposed presser blocks E—E, each of which is fastened to the outer end of a horizontally disposed 20 shank bar e, which slides in a suitable carrier e' secured by screws or other suitable fastening devices e² to the side of the middle form block. The inner end of each shank bar e is provided with an up- 25 turned or vertically extending arm e³, these arms e³ of the two blocks normally lying slightly spaced apart at the center line of the form block when the device is not in operative position, for I provide a contraction 30 spring S, which is connected at its ends to eyes s fastened to the blocks E—E, the tendency of the spring being to draw the two blocks inward or toward each other, as shown in Fig. 1. The upper end of each 35 up-turned arm e³ is beveled as at e⁴ for the convenient reception of the V-shaped end portion f of the wedge plate F, which is screwed or otherwise secured at f' to the side of the top form block B, this wedge 40 when moved, as hereinafter described, thrusting itself between the pair of arms e³ and thus sliding or forcing the blocks E outward or away from each other and into contact with the inturned flaps d, as shown 45 in Fig. 3.

Before these vertical flaps d are pressed by the blocks E they are turned or tucked in by suitable mechanism, which as it forms no part of the present invention, need not 50 be described. When so tucked in, these turned in ends assume the position shown in Figs. 1 and 2, without being positively pressed against the inner side of the box or box lid. The box or box lid D is held 55 between the middle form block A and the bottom form block C, as shown in Figs. 2 and 3, and the sides of the box or box lid are also supported externally by the usual external pressers employed in this class of 60 machine. The middle form block A is

raised and lowered by the central rod a passing through an opening in the top form block B, which latter is raised and lowered upon the rod a by suitable separate mechanism. Prior to the pressing action of the 70 blocks E upon the flaps d the upper form block B is raised above the middle form block A, as shown in Fig. 2, so that the pressing blocks E—E are drawn back to allow the flaps d to be turned in. When 75 the top form block descends the wedge F enters between the beveled ends of the up-turned arms e³ of the shank bars carrying the presser blocks E—E and thus drives the presser blocks apart, as shown in Fig. 3, 80 causing the outer faces of the blocks to press firmly upon the flaps d so the latter are caused to adhere properly, firmly and closely to the inner sides of the box or box lid. When the top form block B is lifted clear 85 of the middle form block A the spring S draws back the blocks E—E into the position shown in Figs. 1 and 2 ready for the next operation.

In the modification shown in Fig. 4, in 90 place of the wedge F, a plate F' is secured to the top form block not shown, this plate having two diagonal slots g converging toward their lower ends, are arranged in wedge formation. Through these slots pass 95 the pins g' carried by the shank bars g² of the presser blocks E'—E'. When the top form block is lowered, the slots and pins cause the blocks E'—E' to expand as indicated in the dotted lines in Fig. 4, while 100 the raising of the top form block causes the presser blocks E'—E' to be drawn back into normal position by the positive action of the slot and pin connections. In the form of device shown in Fig. 4 the shank 105 bars g² slide in the grooved or slotted plates g³ instead of through carriers, such as shown in e' and Figs. 1-3 inclusive.

While I have herein shown and described certain embodiments of my invention, I 110 wish it to be understood that I do not limit myself to all the precise details of construction herein set forth by way of illustration, as modification and variation may be made without departing from the spirit 115 of the invention or exceeding the scope of the appended claims.

It will be understood, for instance, that the pressing blocks may be arranged and adapted for different depths of boxes or 120 lids, and that the pressing blocks may be mounted for sliding in any suitable or preferred manner.

What I claim is:

1. In a box covering machine of the character described and adapted to press the in-turned flap of a covering against the inside of a box, the combination with a support for the box, of a sliding member in the plane of the support and positioned within the box 125 130

out of the path of movement of the flap during the flap-inturning movement, and means for forcing said sliding member into contact with the flap to press said flap against 5 the adjacent face of the box.

2. In a box covering machine of the character described and adapted to press the inturned flap of a cover against the inside of a box, the combination with a support for 10 the box of a laterally sliding member within the box during the flap-inturning movements, and a reciprocating member for forcing said sliding member into contact with the flap, to press said flap against the adjacent face of the box.

3. In a box covering machine of the character described and adapted to press the inturned flap of a cover against the inside of a box, a pair of sliding pressing blocks within 20 the box during the flap-inturning movements and means for forcing said pressing blocks in opposite directions and into contact with the inturned flaps to press said flaps against the adjacent faces of the box.

4. In a box covering machine of the character described, a form block, a pair of sliding presser blocks within the box during the flap-inturning movements, a second form block, and a member carried by the second 30 form block for actuating the presser blocks and moving them into surface contact with the cover flaps.

5. In a box covering machine of the character described, a form block, a pair of oppositely sliding presser blocks mounted on the form block and adapted to contact with inturned flaps, and an expanding device adapted to actuate said blocks to move the latter outwardly.

6. In a box covering machine, of the character described, a form block provided with a pair of sliding pressing blocks adapted to contact with flaps to be pressed, a second form block movable relative to the first form 40 block and having an expanding device adapted to actuate the sliding blocks to force the latter outwardly in opposite directions, and means for returning said form blocks inwardly to normal position.

7. In a box covering machine of the character described, a pair of sliding blocks

positioned within the box during flap-inturning movements and adapted to contact with flaps to be pressed, each block having a shank member, with the inner ends of said shanks lying adjacent each other, a wedge member adapted to be moved and inserted between the shank members to force said blocks outwardly and means for drawing said blocks inwardly after the wedge has 55 been withdrawn.

8. In a box covering machine of the character described, a form block, a pair of presser blocks carried by sliding on the form block, and a second form block having a depending wedge adapted to move downwardly 60 between the presser blocks to force the latter outward.

9. In a box covering machine of the character described, a pair of sliding presser 70 blocks positioned within the box during flap-inturning movements and adapted to contact with flaps to be pressed, a shank bar connected with each presser block, and means engaging the shank bars for moving 75 said presser blocks outwardly in opposite directions.

10. In a box covering machine adapted to produce box elements with turned-in vertical flaps, means for pressing such inturned 80 flaps against the inside of the box element, said means including slideable presser members within the box element during flap-inturning movements and normally out of the path of movement of the flaps while being 85 inturned and movable into contact with such flaps when inturned, and means for moving said members.

11. In a box covering machine of the character described, a vertically-reciprocating 90 form block having recesses to permit free infolding of flaps, and a presser block structure carried by the form block and movable horizontally into such recesses when the flaps have been inturned.

In testimony whereof I have hereunto set my hand in the presence of two subscribing witnesses.

EDWARD THOMAS BURLTON.
